UNITED STATES PATENT OFFICE.

WILLIAM B. CLEVES AND FRANCIS G. RYAN, OF BRATTLEBOROUGH, VT.

COMBINED FOOT-TREADLE AND ROD.

SPECIFICATION forming part of Letters Patent No. 322,793, dated July 21, 1885.

Application filed September 1, 1884. (No model.)

To all whom it may concern:

Be it known that we, WM. B. CLEVES and FRANCIS G. RYAN, citizens of the United States, and residents of Brattleborough, in the county 5 of Windham and State of Vermont, have invented certain new and useful Combined Foot-Treadle and Rod, of which the following is a specification.

Our invention relates to a novel construction 10 of a foot-treadle particularly adapted for sewing-machines, but may be made so as to be attached to any foot-power machine.

The first part of our invention consists of a treadle-rod made of any suitable material, 15 preferably metal. The extreme ends of the treadle-rod are provided with means for properly securing the same to the standards or legs of the machine. The rod is also provided with what is usually termed "scale" or "angle" 20 bearings, located near the ends of the treadle-rod. These bearings abut against a plane surface, which surface forms a shoulder which projects slightly above the vertex of the angle forming said scale-bearings, which terminate in a T-shaped body extending from 25 bearing to bearing. In the center of the shank of the T is provided in the first device, as shown in Figures 2 and 4, a roller mounted in the rod; or, in the second device, a recess extending upward to a line level with the apexes 30 of the angle-bearings, as shown in Figs. 6 and 7; or, in the third device, a vertical aperture extending through the rod, as shown in Figs. 35 8 and 9, either of these devices being used in securing the treadle to the rod.

The second part of our invention consists of a treadle made of any suitable material, preferably of metal, provided with angular grooves in the under side thereof near the side edges, 40 the surface of said treadle above said grooves abutting against the shoulder which is formed on the rod. The central portion of the treadle is provided with a guard, which guard bears upwardly against the roller in the rod in the first device, or with a bracket having a lug projecting upward beneath the center of the rod, which lug terminates in an angle-bearing which rests against the under surface of the rod in the recess in the second device; 45 or with a vertical aperture for the passage of the shank of the T-shaped bolt in the third

device. Either of these devices may be used for securing the treadle firmly to the rod, allowing it to move freely within the limited arc required.

In the drawings, Fig. 1 represents a vertical section through one of the scale or angle bearings, showing the manner in which the treadle rests thereon. Fig. 2 represents a cross-section taken through the center of the treadle and rod, and shows the first device for securing the treadle to the rod by means of the guard *c* bearing upon the roller *b*. Fig. 3 is a vertical section taken through *xx*. Fig. 4 is a section taken through *yy* with the same device as in Fig. 2. This figure illustrates by dotted lines the manner in which the treadle is mounted on the treadle-rod. Fig. 5 represents detail views of the ends of the treadle-rod. Fig. 6 represents a cross-section taken 50 through the center of the treadle and rod, showing the second device for securing the treadle to the rod, a bracket, *c*, fixed to the treadle by screws having an upward-projecting lug, *c*, its sharp edge bearing against the under 55 surface of the rod in the recess *b* in direct line with the angle-bearings *b*. A rubber pad, *h*, may be inserted between the rod and the lug. Fig. 7 represents a section taken through *yy* in the device shown in Fig. 6. Fig. 8 represents a cross-section taken through 60 the treadle and rod, showing the third device for securing the treadle to the rod, a T-shaped bolt, *g*, its arms *g* resting in a recess in the treadle, centering with the angular 65 grooves *c* at either end of the treadle *c*, its shank passing downward through the rod and secured by a nut, which nut is screwed up 70 against a washer, *h*, of rubber.

Similar letters refer to similar parts throughout the drawings, in which *a* represents the standards or legs of an ordinary sewing-machine. *b* is the treadle-rod, provided with a vertical tongue, *f*, on each end thereof. The tongue is integral with the treadle-rod *b*, and is so constructed as to form the shoulders *f*. *f* are the ears of the treadle-rod, provided with the screw-bolt *f* for securing the same to the standard or leg. *d* is a brace-rod, provided with a forked end, which forked end fits over the vertical tongue *f*. *b* is the shoulder, terminating in the scale or angle bearing

b^2 , integral with the T-shaped portion b^3 of the treadle-rod b . b^4 is a roller of rubber or other suitable material, mounted in the rod b . b^5 is the recess in the rod b for the reception of the lug c^3 . This recess may be made deeper and the space between the surface of the rod and the lug be filled with rubber or other resilient substance in order to give a yielding surface for the adjustment of lines of bearing, or for preventing lost motion by wear. b^6 is a vertical aperture in the rod for the passage of the T-bolt g . c is the treadle. c^1 is the guard integral therewith or attached thereto, and which bears against the roller b^4 . c^2 is the bracket, secured to the treadle and having a lug, c^3 , projecting upward against the rod b in the recess b^5 . c^4 is a seat or bearing in the treadle for the rounded arms of the T-bolt g . c^5 are angular grooves in either end of the treadle. The vertex of the angle forming the grooves rests on the vertex forming the angle of the bearings b^2 on the rod.

In Fig. 4 is represented the manner in which the treadle is mounted on the treadle-rod when the first device for securing it thereto is used. It will be obvious that when the rod shall have been properly secured to the legs it cannot roll or move from its vertical position, and that when the treadle shall have been properly mounted on the treadle-rod, the shoulders b' will prevent any lateral motion being imparted to the treadle when in operation, and the guard c' or bracket c^2 or bolt g will prevent a vertical motion, while allowing a free movement of the treadle on its bearings within the limited arc desired, and the insertion of a resilient substance at the point of contact in the center of the treadle and rod, either as a roller in the first device or as a pad in the second device, or as a washer in the third device, serves to take up lost motion by reason of misfit or wear, to prevent noise, and to relieve the rigidity of actual metallic contact.

Having thus described our invention, what we claim as new, and desire to secure by Letters Patent, is—

1. In combination with a foot-power machine, a treadle and rod adapted to be held rigidly in proper position without collars, set-screws, or other movable devices.

2. The treadle c , provided with the guard c' and angular grooves c^5 , in combination with the treadle-rod, as herein described.

3. The treadle c , provided with the bracket c^2 , its angle-bearing c^3 , and angular grooves c^5 , in combination with the treadle-rod, substantially as herein described.

4. The treadle c , provided with the recess c^4 and angular grooves c^5 , in combination with the treadle-rod, substantially as herein described.

5. The treadle-rod b , provided with the vertical tongues f at their extreme ends, shoulders f' , ears f^2 , screws f^3 , the shoulders b' , scale or angle bearings b^2 integral with the T-shaped portion b^3 , roller b^4 on the bottom of the shank of the T, in combination with a

treadle of a foot-power machine, substantially as shown and described.

6. The treadle-rod b , provided with the vertical tongues f at their extreme ends, shoulders f' , ears f^2 , screws f^3 , the shoulders b' , scale or angle bearings b^2 integral with the bottom portion, b^3 , recess b^5 , in combination with a treadle, c , with angular grooves c^5 , bracket c^2 , with its angle-bearing c^3 resting against the rod b at its center in line with and in opposition to the bearings formed on the rod at b^2 and the treadle at c^5 , substantially as shown and described.

7. The treadle-rod b , provided with scale or angle bearings b^2 integral with the bottom portion, b^3 , in combination with a treadle, c , with its angular grooves c^5 , recess c^4 , and the T-bolt g , substantially as shown and described.

8. The brace-rod d , provided with a forked end adapted to fit over the vertical tongues f of the treadle-rod b , in combination with the recessed legs adapted to receive the ears f^2 of the treadle-rod, and adapted to be secured thereto by screws f^3 , substantially as shown and described.

9. The combination, substantially as shown and described, consisting of the treadle c , with its angular grooves c^5 , resting on the scale or angle bearings b^2 , a portion of the treadle abutting against the shoulders b' of the treadle-rod, the shoulders adapted to prevent lateral motion, the guard c' of the treadle engaging with the roller b^4 in the treadle-rod, the guard adapted to prevent a vertical motion, the ends of the rod provided with means for attaching it to a sewing-machine and resting in recesses in the legs to prevent rolling motion or any departure from the vertical line.

10. A treadle having angular grooves at either end resting on scale or angle bearings in a rod or fixed support, and held thereto by means of a third bearing upward against the rod and downward upon the treadle, which bearing shall be intermediate between the terminal bearings.

11. In a treadle having a rocking movement, two scale or angle bearings, in combination with a third bearing, a connecting-link intermediate between the terminal bearings, holding the treadle firmly to its fixed support while allowing it to rock freely.

Signed at Binghamton, in the county of Broome and State of New York, this 2d day of August, 1884.
